UNITED STATES PATENT OFFICE.

GEORGE M. SICKLESTEEL, OF NORTH BRANCH, MICHIGAN.

SHAFT-TUG.

SPECIFICATION forming part of Letters Patent No. 341,063, dated May 4, 1886.

Application filed August 17, 1885. Serial No. 174,533. (No model.)

To all whom it may concern:

Be it known that I, GEORGE M. SICKLESTEEL, of North Branch, in the county of La-
peer and State of Michigan, have invented a
5 new and Improved Shaft-Tug, of which the
following is a full, clear, and exact descrip-
tion.

The object of my invention is to provide a
10 new and improved shaft-tug which holds the
shaft or thills and prevents them from drop-
ping, even if the brace or whiffletree breaks,
and also to prevent the vehicle from running
on the horse in case of breaking of the shaft
or tree.

15 The invention consists in the construction
and combination of parts and details, as will
be fully set forth and described hereinafter.

Reference is to be had to the accompanying
20 drawings, forming part of this specification,
in which similar letters of reference indicate
corresponding parts in all the figures.

Figure 1 is a side view of my improved
shaft-tug. Fig. 2 is a front view of metal
25 plate and hook. Fig. 3 is a longitudinal face
view of the billet.

The metal strap or plate A is provided
with three or more loops, B, on its outer sur-
face, and with a transverse slot, C. A pin, D,
30 projects from the plate or strap A.

The strap E, which is secured to the saddle-
pad, is passed through the loops B and through
the slot C, the pin D passing into an aperture
35 in the strap, and thus preventing the strap
from moving lengthwise.

The lower end of the strap or plate A is
bent to form a hook, F, having its end bent
40 down to form a nose, G.

The billet H has a widened part, J, which
is placed in the hook F in the manner shown,
45 and is held in place by rivets K. The billet
is provided on its inner end with a tongue, L,
which is passed through a slot in the end of
the hook directly below the nose G.

The billet H has a longitudinal slot, M, on
one end of which a transverse metal plate, N, 45
is secured, against which the nose G rests.

Before the shaft is placed in the hook F the
billet H is raised, as shown in dotted lines in
Fig. 1, and after the shaft has been placed in
the hook the billet is swung down, the nose G 50
passing through the slot M. The thill is held
securely, and cannot drop in case the billet
breaks or slips, as the hook F holds the thill.

The tug is very simple in construction, strong
and durable, and can be used for thills of all 55
sizes without any change in shaft-bearer or
belly-bands.

Having thus described my invention, what
I claim as new, and desire to secure by Letters
Patent, is—

1. The combination, with the metal plate A,
provided with the hook F, of the billet H, hav-
ing the slot M, substantially as herein shown
and described.

2. The combination, with the metal plate A, 65
having the hook F, of the strap or billet H,
having the slot M, and the tongue L, passed
through a slot in the end of the hook, sub-
stantially as herein shown and described.

3. The combination, with the metal plate A, 70
having the hook F, provided with nose G on
its end, of the billet or strap H, having the slot
M and the cross-piece N at the end of the slot,
substantially as herein shown and described.

4. The combination, with the plate A, hav- 75
ing the slot C, the hook F, and the bands B,
of the strap E and the billet H, substantially
as herein shown and described.

5. The shaft-tug plate consisting of a body
or shank and a hook, and having a lateral 80
slotted bend or offset at the juncture of such
shank and hook, substantially as set forth.

GEO. M. SICKLESTEEL.
